UNITED STATES PATENT OFFICE.

HARRY LOUIS OLDEN, OF CINCINNATI, OHIO.

SHEET-METAL ROOFING.

Application filed November 30, 1920. Serial No. 427,401.

To all whom it may concern:

Be it known that I, HARRY LOUIS OLDEN, a citizen of the United States, and residing at Cincinnati, in the county of Hamilton and State of Ohio, have invented a new and useful Improvement in Sheet-Metal Roofing, of which the following specification is a full disclosure.

This invention relates to a sheet metal roofing and particularly to the crimping at the opposite longitudinal edges of the sheets to provide for registration and overlapping of the relative opposite edges of two adjacent sheets for making a water-proof joint and rigid nailing ridge when the sheets are applied for roofing and the like covering.

In my invention the opposite parallel edges of each sheet has formed thereon crimped reenforcing beads of different cross-sectional configuration, one form of bead overlapping the other to form a rigid water-proof and water-conveying laminated joint.

An object of my invention is to provide a form of reenforced water-proof joint which cannot be crushed by the workmen when driving the necessary nails therethrough to fasten the jointed sheets, when applying as a roof covering.

An additional object is to so shape the reenforcing elements of the joint that draining ways are provided at the interior of the same, along which any water forced within will be quickly and positively drained from the joint, thus preventing deterioration of the material and avoiding the possibility of an overflow of water to the under surfaces of the metal roofing.

Another object is to prevent capillary action within and between the reenforced seams.

Other objects and advantages will be disclosed in the description of the drawings, forming a part of this specification, in which:

Fig. 1 is a fragmentary perspective view of a metal sheet having formed upon two of its parallel edges reenforcing beads of special configuration.

Fig. 2 is a sectional view taken through a plurality of sheets, with their relative opposite edges registered and overlapped to form water-tight seams or joints, as applied to a roof.

Fig. 3 is an enlarged detail section of my improved laminated water-tight seam.

Fig. 4 is a fragmentary plan of the structure shown in Fig. 3.

Figs. 5 and 6 are detail perspective views showing the crimp formation of the two opposite edges of the sheet.

Fig. 7 is a view similar to Fig. 3, showing a modified form.

The numeral 1 designates a sheet of roofing material of any preferred dimensions, provided on one of its edges, preferably its longitudinal edge, with a V-shaped upwardly directed crimp 2, primarily as an overlapping or tapping crimp, and on its opposite parallel edge with a substantially V-shaped upwardly-extending longitudinally-corrugated reenforcing crimp 3 of special cross-sectional configuration, primarily as an underlying or lower crimp. 75

The crimps 2 and 3 may be designated as ridges and the side walls of the crimp or ridge 3 are corrugated longitudinally and toward the base thereof, to strengthen the ridge and break continuous contact between the adjacent walls of nested ridges of two sheets in making a joint or seam.

As best seen in Fig. 3, the cover crimp 2 overlaps the reenforcing crimp 3, the apices 4 and 5 of the crimps being in contact. The sides 5^a and 5^b of the reenforcing crimp 3 are spaced from the sides 6 and 6^a of the cover crimp 2, to provide air spaces 7 between the two crimps; these spaces in conjunction with certain bends, hereinafter described, acting as drain-ways for disposing of any water which may be driven between the reenforced seam, and also acting to prevent capillary action therebetween.

Adjacent the lower ends of the sides 5^a and 5^b, of the reenforcing crimp 3, are formed reserve bends 8 and 9, as longitudinal corrugations, the outer side of the bend 8 being slightly spaced from the inner surface of the wall 6, of the cover crimp 2, and the bend 8 is formed with a vertical downwardly extending wall 10, merging into the flat horizontal portion of the sheet 1. The bend 9, of the side of 5^b, is formed with a downwardly and outwardly extending straight portion 11, lying parallel and in contact with the inner surface of the slanting side 6^a of the cover crimp 2, the lower end of the said portion 11 abutting the roof board. 105

The reenforcing crimp 3 thus acts as a stiffener for the seam or joint and in virtue of its spaced relation to the cover crimp, provides drain-ways and prevents capillary action between the two crimps, as before stated. The seam is fastened by nails 15, driven through the apices of the crimps, lead disks or packing washers 16, being placed between the heads of the nails and against the upper surface of the cover crimp, to prevent entrance of water through the nail openings. The lower end 17, of the side 6, of the cover crimp abuts the upper surface of the sheet 1, the opposite side 6^a merging into the flat horizontal portion of the said sheet.

A modified form of my invention is shown in Fig. 7, in which the crimp 3^a is placed over the crimp 2^a, the upper portions of the slanting walls of the crimps contacting one another. The reverse bends 8^b and 9^b of the crimp 3^a, by their relations to the outer surfaces of the crimp 2^a, form the draining passages 20, similar to the other form of my invention.

My improved reenforced seam or joint

has been found exceedingly efficient in preventing the entrance of water into its interior and provides a very rigid structure, resisting to a marked degree the strains incident to the driving of the fastening devices used in its attachment.

Having described my invention, what I claim is:

A metal roofing sheet having non-complementary V-ridges along two opposite ends thereof, adapted for relative ridge nesting for lap joining two sheets to provide a connecting seam, with the crowns of the nested ridges in contact, one ridge of the sheet having its opposite walls and at the base thereof corrugated longitudinally for breaking a continuous contact between the walls of the non-complementary ridge when nested to form a connecting seam.

In witness whereof, I hereunto subscribe my name, as attested by the two subscribing witnesses.

HARRY LOUIS OLDEN.

Witnesses.
